(57) **CLAIM**

The ornamental design for a stringer connector bracket, as shown and described.

DESCRIPTION

FIG. 1 is a left side view of a stringer connector bracket; FIG. 2 is a right side view of the stringer connector bracket; FIG. 3 is a top view of the stringer connector bracket; FIG. 4 is a bottom view of the stringer connector bracket; FIG. 5 is a front view of the stringer connector bracket; FIG. 6 is a rear view of the stringer connector bracket; FIG. 7 is a side angled perspective view of the stringer connector bracket; and, FIG. 8 is another side angled perspective view of the stringer connector bracket, showing the string connector bracket in an environment of use.

The broken lines shown in FIG. 8 illustrate environment and form no part of the claimed design.
